INVENTOR

BY *Victor J. Evans*
ATTORNEY

Arthur Evans Jr.
WITNESS:

UNITED STATES PATENT OFFICE

STANLEY PENKOSKI, OF NEW YORK, N. Y.

TWO-IN-ONE CHISEL

Application filed October 1, 1930. Serial No. 485,741.

The object of this invention is the provision of a chiseling tool that comprises a member provided with two cutting bits and which is designed for easily and expeditiously performing a number of functions, such for instance, as the longitudinal splitting of cord wood, the grooving of timbers along scribed lines or the notching of solid newel posts that receive in the said notches the lower step of a stairway and which tool is characterized by simplicity in construction and reliability.

To the attainment of the foregoing the invention consists in the improvement herein-after described and definitely claimed.

15 In the drawing:

Figure 1 is an elevation of a tool employed for splitting cord wood.

Figure 2 is an enlarged side elevation of the tool per se.

20 Figure 3 is a similar view but illustrating a slight modification.

Figure 4 is an end view looking toward one of the bits.

My improved chiseling tool is constructed 25 of a single piece of hard steel or like material and includes two spaced shanks 1-1 that are sharpened on one or on both of their faces to provide the outer edges thereof with bits 2. The shanks 1 merge into inwardly 30 inclined arms 3, and the said arms, at their connected portions have a central extension in the nature of a head 4. By reference to the drawing it will be noted that the arms 3, have their outer faces, at the juncture with 35 the shanks 1 substantially flattened, as at 5, providing shoulders, while in Figure 3 the shanks 5' are extended or projected a suitable distance above the arms 3' to provide shoulders 6 that are spaced away from the

40 arms. It is, of course, to be understood that the tool is to be made in different sizes and that the shanks 1 may be arranged close together or spread a material distance apart. Also it is to be understood that the tool, except for the sharpened bit portions 2 may

be round or square in plan and when the tool is employed for splitting logs as disclosed by Figure 1 of the drawing the shanks 1 have their opposite faces beveled to points to provide the bit disclosed by the full lines in Figure 4 of the drawing. The tool, when partly forced into the log by the impact of the force of a sledge or the like will cause the log to split into slats in an easy and expeditious manner. The shoulders 5 or 6 provide a means whereby the hammer may be directed against either of the shanks and consequently either of the bits.

It will be readily noted that the spaced bits, can be readily arranged upon a scribed line and that a timber may be grooved or split along such line. After the bit has been forced into the timber for a determined distance and a groove in the timber is desired one of the bits may be forced longitudinally through the slots or openings made by the pair of bits through the impact of force delivered against the shoulder and the shank therefor so that the cut wood can be thus forced out to produce the complete groove. The tool is also especially desirable for use in notching the corners of solid newel posts, which with the ordinary construction of chisels involves a laborious task on the part of the carpenter, as the two bits cutting along the scribing lines on the newel posts will easily and quickly remove the corner of the newel posts.

While I have herein illustrated a satisfactory embodiment of my improvement my features of invention are capable of extended application and I do not wish to be limited to the specific structure herein shown and described.

Having described the invention, I claim: 85
A wood working and splitting tool comprising a pair of spaced parallel shanks having wedge-shaped lower ends terminating in cutting edges and provided at their upper ends with impact surfaces parallel with said 90

cutting edges, there being inclined arms
springing from the upper inner side por-
tions of said shanks and inclined at equal an-
gles with relation to each other, said arms
merging with each other at their upper ends
and merging with an upstanding head por-
tion, said head portion being midway be-
tween the shanks and parallel thereto, and
provided at its upper end with an impact sur-
face lying parallel with all of the cutting
edges.

In testimony whereof I affix my signature.
STANLEY PENKOSKI.
